J. E. B. HOLLADAY,
MICROPHONE TRANSMITTER,
APPLICATION FILED JUNE 17, 1916.

1,246,429.

Patented Nov. 13, 1917.

Joseph E. B. Holladay, Inventor
By Vernon Goddard, His Attorney

UNITED STATES PATENT OFFICE.

JOSEPH E. B. HOLLADAY, OF SUFFOLK, VIRGINIA, ASSIGNOR TO THE HOLLADAY DETECTO COMPANY, INC., OF SUFFOLK, VIRGINIA, A CORPORATION OF VIRGINIA.

MICROPHONE-TRANSMITTER.

1,246,429.

Specification of Letters Patent. Patented Nov. 13, 1917.

Application filed June 17, 1916. Serial No. 104,213.

To all whom it may concern:

Be it known that I, JOSEPH E. B. HOLLADAY, a citizen of the United States, residing at Suffolk, in the county of Nansemond and 5 State of Virginia, have invented certain new and useful Improvements in Microphone-Transmitters, of which the following is a specification.

This invention relates to microphone 10 transmitters, a type particularly adapted for use in combination with a sensitive receiver for the purpose of greatly amplifying the sensitiveness of the instruments, whereby any slight sound or vibration may be detected at the receiving end.

In the accompanying drawings, Figure 1, is a plan view of the instrument with the cover removed;

Fig. 2 is an enlarged sectional view taken 20 on line 2—2 of Fig. 1.

Fig. 3 is a rear view; and

Fig. 4, shows various elements which go to make up the transmitter, (excepting the granular carbon) showing said parts in the 25 relative positions they assume when assembled.

The numeral 1, indicates a casing or back exteriorly threaded at its open end as at 2. A circular cap or face plate 3 perforated at 30 its center is provided upon its interior with threads 4, which threads are adapted to be received by the threaded portion 2 of the base plate.

An annular metal ring 5 is received within 35 the wall portions of the base 1, being of a sufficient diameter and thickness to be frictionally held therein; the upper surfaces of said ring and wall portions being flush with each other. An insulating disk 6 is secured 40 to the back 1, being of a sufficient diameter to be snugly received within the inner diameter of the metal ring 5. Mounted upon this insulating disk is a metal disk 7, which is secured to the back 1 by suitable fastening

45 screws 8, 9 and 10. The screws 8 and 10 are surrounded by suitable insulating bushings 11, which serve to insulate the screws from the metal disk 7.

A terminal 12 is secured to screw 8, which, 50 as disclosed in Fig. 1, completes a metallic circuit between one side of the circuit to the metal casing 1, while the screw 9, as shown in Fig. 2, is adapted to secure a terminal 13 direct to the disk 7. Mounted upon 55 the metal disk 7 is a circular carbon block 14

secured thereto by a screw 15. The head of said screw being slightly below the upper surface of the carbon block. Around the center of said carbon block is a series of hemispherical cavities 16 having highly polished faces, and being partly filled with a conducting medium 17, in the present instance, granular carbon. More or less of these granular carbons are used according to the length of wires used, or rather according to the increased or decreased resistance.

An insulating mica ring 18 is received upon the outer face of the metal ring 5 and wall portions of the back 1, upon which is adapted to rest a carbon diaphragm 19. The 70 relative position of said carbon block 14 with respect to said diaphragm 19 is such that while the said block does not actually contact the said diaphragm, yet they are so intimate that the carbon granules contained 75 in said cavities will not escape, and are held therein by said diaphragm.

Resting upon the carbon diaphragm 19 is a card board washer 20, which forms an insulated core for a wire coil 21.

It will be noted in Fig. 2, the diameter of the carbon diaphragm is slightly less than the inside diameter of the cap 3, while the diameter of the said coil is practically the same as the diameter of the said cap, thereby 85 forming an electrical connection between the two, which coil in turn transmits current to the said carbon diaphragm 19.

Thus it will be seen that a transmitter constructed as above described is capable of 90 high efficiency principally by the introduction of the wire coil directly above the carbon diaphragm 19, which coil serves as the electrical conductor between the carbon diaphragm and the metallic cap 3, which in 95 turn is in contact with the back plate 1, which is connected to the opposite side of the line from that of the carbon block 14.

I claim:

1. In a transmitter, the combination of an electrode, a diaphragm electrode arranged across the face of said electrode, and a coil arranged upon the outer face of the said diaphragm and in electrical connection therewith.

2. In a transmitter, the combination of a back plate, a metal disk connected to but insulated therefrom, an electrode connected thereto, a diaphragm electrode arranged across the face thereof, an annular electrical 110

coil arranged upon the outer face of the said diaphragm electrode and in electrical connection therewith, and a perforated cap or face plate adapted to surround said diaphragm electrode and coil for securing them in place, said face plate and back plate being detachably secured together.

3. In a transmitter the combination of a back plate, an annular ring arranged within the wall portions of said back plate, a metal disk connected to but insulated from said back plate, a carbon block electrode provided with pockets, carbon granules arranged within the said pockets, a diaphragm electrode received upon but insulated from said annular ring, and arranged across the face of said carbon block electrode, an annular electrical coil arranged upon the outer face of the diaphragm electrode, and a perforated cap or face plate adapted to sur-

round said carbon diaphragm or coil for securing them in place, said face plate and back plate being detachably secured together.

4. In a transmitter, the combination of a carbon block electrode provided with pockets, carbon granules arranged within said pockets, a carbon diaphragm electrode arranged across the face of said carbon block electrode, spaced apart therefrom, and in contact with said carbon granules, and a coil arranged upon the outer face of the said carbon diaphragm and in electrical connection therewith. 25

5. A transmitter, comprising oppositely disposed electrodes and an annular coil arranged upon one of the electrodes and in electrical connection therewith. 30 35

In testimony whereof I affix my signature.
JOSEPH E. B. HOLLADAY.
